UNITED STATES PATENT OFFICE

110,333

DESIGN FOR A TOILET BOTTLE

Iuliu Aizic, New York, N. Y.

Application April 13, 1938, Serial No. 76,469

Term of patent 3½ years

To whom it may concern:

Be it known that I, Iuliu Aizic, a citizen of Rumania, residing at New York city, county of New York, Borough of Manhattan, and State of New York, have invented a new, original, and ornamental Design for a Toilet Bottle, of which the following is a specification, reference being had to the accompanying drawing, forming a part thereof.

I claim:

The ornamental design for a toilet bottle as shown,

IULIU AIZIC.
